UNITED STATES PATENT OFFICE.

JOHN R. KLUG, OF MUNDAY, TEXAS.

FOLDING CRATE.

Application filed July 17, 1923. Serial No. 652,096.

To all whom it may concern:

Be it known that I, JOHN R. KLUG, a citizen of the United States, residing at Munday, in the county of Knox and State of Texas, have invented certain new and useful Improvements in Folding Crates, of which the following is a specification.

This invention relates to folding crates, and more particularly to a collapsible shipping crate which may be employed for shipping poultry, eggs, fruit, or any other material, and which may be readily folded into compact form to be returned to the shipper or stored in a minimum space for future use.

One of the objects of the invention is to provide a folding crate of this character which may be cheaply manufactured and which may be strong, durable, and readily able to withstand the rough usage to which devices of this character are ordinarily subjected.

Other objects of the invention will appear upon consideration of the following detailed description and accompanying drawings, wherein,

Figure 1 is a perspective view of the folding crate constructed in accordance with my invention,

Figure 2 is a cross section on the line 2—2 of Figure 1,

Figure 3 is a cross section on the line 3—3 of Figure 1,

Figure 4 is a cross section similar to Figure 3, showing the crate folded,

Figure 5 is a longitudinal section through the crate folded,

Figure 6 is a detailed view of the latch hook,

Figure 7 is a detailed view showing the manner of holding the parts together when folded,

Figure 8 is an elevation of the crate showing the manner of constructing it of wire mesh,

Figure 9 is a side elevation of the same, and

Figure 10 is a cross section of the line 9—9 of Figure 9.

Referring to the drawings by numerals, the crate consists of the top wall 1 and the bottom 2 forming the cover and floor of the crate respectively. The longitudinal corners of the crate are provided with the retaining bars 3 and the end bars 4 forming the top retaining frame within which the top cover

1 is hingedly mounted by the hinges 6. The top wall 1 is also provided with hook members 7 engageable with eyelets 8 in the retaining bars 3 of the top frame, so that the cover may be held in operative position.

The front and back walls 9 and 10 respectively each consist of sections 11 and 12 hingedly connected at their meeting edges by the hinges 13, and having their opposite edges hingedly connected to the fastening hooks 14 which are carried by the top and bottom of the crate, thus permitting the sections 11 and 12 to swing inwardly as shown in Figure 4 when the crate is folded.

The end walls 15 are provided with openings around the marginal edges to receive pins 16 which project from the end edges of the top, bottom and side walls, and the corner pins 16¹ are provided with openings to receive fastening hooks 17 which are pivotally mounted upon the end walls to be swung into position when the crate is erected, as in Figure 1.

When the crate is to be collapsed and folded, the hooks 17 will be disconnected so that the end walls 5 may be removed from the pins 16, whereupon the side walls 9 and 10 will be folded, as shown in Figure 4, and the end wall sections 15 will be thrust into the spaces between the folded side walls and the top and bottom walls respectively, thus compactly retaining the entire structure in a relatively small space.

To bind the structure in folded position, a hook 18 and a chain 19 is employed between the top cover 1 and the bottom wall 2, as shown in Figure 7, thus permitting the hook to be hooked into one of the links of the chain 19 for maintaining the structure in tightly closed position.

Figures 8, 9 and 10 of the drawings illustrate the structure as it appears when constructed of wire mesh, as will be desirable when the crate is constructed to contain poultry or other farm products requiring free ventilation of the crate.

Minor changes may be made in the details of construction without departing from the spirit of the invention or the scope of the claims hereunto appended.

What I claim as new and desire by secure by Letters Patent is:

1. A collapsible shipping crate having a top, bottom, side and end walls, a top frame comprising longitudinal retaining bars and transverse retaining bars forming a rectan-

5   gular frame, the top wall being hingedly mounted in the frame, the said side walls being of sectional construction and consisting of upper and lower sections hingedly connected at their meeting edges for inward folding movement of the said side walls, the remote edges of the said side wall sections being hingedly connected to the said longitudinal retaining bars in the said 10 frame, the end edges of the said top frame, side walls, and bottom wall being provided with outwardly projecting pins, the end walls having their marginal edges equipped with openings to receive the said pins whereby 15 the end walls may be attached to the said end edges of the other walls, and latch hooks to retain the said end walls in position on the said pins.

20   2. A collapsible shipping crate having a top, bottom, side and end walls, a top frame comprising longitudinal retaining bars and transverse retaining bars forming a rectangular frame, a top wall being hingedly mounted in the frame, the said side walls 25 being of sectional construction and consisting of upper and lower sections hingedly connected at their meeting edges for inward folding movement of the said side walls,

the remote edges of the said side wall sections being hingedly connected to the said longitudinal retaining bars in the said frame; the end edges of the said top frame, side walls, and bottom wall being provided with outwardly projecting pins, the end walls having their marginal edges equipped with openings to receive the said pins whereby 30 the end walls may be attached to the said end edges of the other walls, and latch hooks to retain the said end walls in position on the said pins, the said frame at the top of the crate having longitudinal strips, the bottom wall also having longitudinal strips, the remote edges of the said collapsible side walls being hingedly connected to the said strips, whereby a space is formed between the said collapsible side walls and the top and bottom walls when the side walls are folded inwardly, said space being adapted 35 to receive the said end walls when they are removed from the pins.

40   In testimony whereof, I have affixed my signature in the presence of two witnesses.

JOHN R. KLUG.
